CLAIM

The ornamental design for a pioneer woman butterfly square fry pan, as shown and described.

DESCRIPTION

FIG. 1 is a bottom plan view of my new design; shown with a cross-sectional view taken through line A-A of FIG. 1.

FIG. 2 is the top plan view thereof;

FIG. 3 is the side elevation view thereof; the opposite side view being a mirror image; and,

FIG. 4 is a perspective view of a fry pan.
